UNITED STATES PATENT OFFICE

161,107

RECEPTACLE FOR FIRE EXTINGUISHING GRENADE

Carl F. Hoelzel, Kansas City, Mo., assignor to Superior Products, Incorporated, Kansas City, Mo., a corporation of Missouri

Application October 31, 1949, Serial No. 5,802

Term of patent 14 years

(Cl. D16—2)

To all whom it may concern:

Be it known that I, Carl F. Hoelzel, a citizen of the United States, residing at Kansas City, in the county of Jackson and State of Missouri, have invented a new, original, and ornamental Design for a Receptacle for Fire Extinguishing Grenade, of which the following is a specification, reference being had to the accompanying drawing, forming part thereof, in which

Fig. 1 is a side elevational view of a receptacle for a fire extinguishing grenade, embodying my new design,

Fig. 2 is a top plan view of the receptacle, and

Fig. 3 is a bottom plan view of the receptacle. The handle, illustrated in Fig. 1, is omitted in Figs. 2 and 3 for convenience of illustration.

The essential features of my design reside in the portions shown in the full lines.

I claim:

The ornamental design for a receptacle for fire extinguishing grenade, substantially as shown and described.

CARL F. HOELZEL.
